UNITED STATES PATENT OFFICE

2,424,270

AUTOMATIC TIMING CONTROL FOR
SCARFING APPARATUS

George C. Ehemann, Jr., Edgewood, and Paul H. Fickenscher, Duquesne, Pa., assignors to Carnegie-Illinois Steel Corporation, a corporation of New Jersey

Application June 25, 1943, Serial No. 492,320

4 Claims. (Cl. 266—23)

1

Our invention relates to a automatic timing control for scarfing or desurfacing apparatus of the character illustrated in United States Letters Patent No. 2,312,418, granted March 2, 1943, to A. M. Keller et al.

In the scarfing or desurfacing of billets and the like, a series of oxygen torches or nozzles are employed to remove a surface layer of metal to remove defects and to otherwise thermally condition the billet for subsequent rolling. As disclosed in the said Letters Patent, apparatus has been provided for manipulating the torches and the work to enable the complete overall surface treatment of the billet or the like, and it is desired to practice the scarfing operation as uniformly as possible.

Although control means have been provided for carrying out the necessary sequential steps in completing the scarfing operations, the same have not been entirely satisfactory. As illustrated in said Letters Patent, a drum-type master controller has been employed whereby the scarfing steps are carried forward by progressively operated control circuits manually energized through the operation of said controller. Such a control is dependent upon the skill of the operator for proper timing, and due to the inability to consistently time the sequential steps, variations have resulted which affect the quality of the scarfing process.

It is a prime object of this invention to provide an automatic timing control for the purposes stated which will be capable of exact and accurate timing sequence between the steps or operations essential to completely and uniformly scarf the work.

Our invention contemplates a single master switch controlling an automatic relay circuit which may be readily adjusted and related to actuate the scarfing apparatus in an efficient and uniform manner.

Additional objects and advantages will become apparent from the following description taken in connection with the accompanying drawing, which drawing schematically illustrates the electrical circuit employed in operative relation with the scarfing apparatus, the latter being diagrammatically illustrated both along and transversely of the pass line of the work to simplify the showing of the complete control circuit in a single view.

Referring to the drawing, the scarfing apparatus is mounted on a carriage, diagrammatically indicated at X, which carriage is adapted to be moved transversely of the pass line y—y of the

2

billet or work x upon suitable wheels 2 and trackway 3 by means of an electric motor 4 and suitable gearing. In this manner, the scarfing device may be positioned for scarfing or removed from the mill operation as desired.

The scarfing device proper includes two banks or series of nozzles or torches, one series A mounted on a slide 5^a being disposed to scarf the upper and one side of the billet x, and the other series 10 B being mounted on a slide 5^b for scarfing the bottom and other side of said billet as the latter passes between said series of nozzles or torches while ignited. Slides or supports 5^a and 5^b are movably mounted for compound motion toward 15 and away from the pass line of the work so as to properly adjust and position the torches or nozzles A and B in relation to the surface of the billet x, the travel of said slides being effected by means of movable horizontal fluid pressure cylinders 6^a and 6^b having their pistons connected with the slides, and fixed vertical fluid pressure cylinders 7^a and 7^b having their pistons connected to said horizontal cylinders 6^a and 6^b respectively.

Controlled means are provided for moving the 20 work or billet, which means are diagrammatically indicated at the right hand side of the drawing and illustrated as being viewed in side elevation with respect to the showing of the cross-section of the billet and the torches or nozzles hereinbefore described. Said means includes a roller table supporting the billet adjacent the scarfing station in which one or more rollers 8 are geared to an electric motor drive 9. A self-retracting pinch roll 10 is mounted above the roller 8 and is movable by a fluid pressure cylinder 11 into contact with the billet when it is desired to move the latter for scarfing.

During the initiation of the scarfing operation and throughout the cycle thereof, the foregoing apparatus is motivated automatically in proper sequence so as to obtain the uniform and efficient scarfing of the billet. Our invention has to do with the automatic control of the entire operation as hereinafter set forth in connection with the description of the control apparatus and the functioning thereof.

Preliminary to the scarfing operation, the carriage X is moved into position through the actuation of a reversing controller 13 in the 45 circuit 14 of the carriage motor 4, the controller being normally connected with a power source 15 by conduits 16, 17 and 18, 19, 20 and 21, the latter conduit 21 containing a normally closed contact c₁ of a relay C, which relay is connected 50 in series with the normally open master control

switch or push button 12 and the power source 15 through conduits 22, 16 and 23, 18.

To initiate the scarfing cycle, the operator closes master switch 12, thereby energizing the relay C, opening contact c1 thereof to interrupt the carriage motor conduit 21 and thereby prevent movement of the carriage X. Normally closed contact c2 of relay C also opens to interrupt the circuit through conduits 21, 24 to the reversing controller 25 in circuit 26 with the table roller motor 9, thereby preventing operation of the table roller 8.

Relay C also has two normally open contacts which close as the relay is energized, contact c3 energizing a second relay D through conduits 18, 27, 28, 17, and contact c4 energizing a motor 29 and a clutch coil 30 therefor, driving an automatic resetting timing relay T, which for example may employ a series of cam-actuated contacts as illustrated. The power for said motor and clutch is supplied from a separate source 30* in circuit with contact c4.

As relay D is energized, its normally closed contact d1 opens and normally open contact d2 closes, said contacts actuating solenoids 31 and 32 respectively, moving valve 33 to the position shown in the drawing, whereby fluid is discharged from the inner ends of the cylinders 6^a and 6^b and high pressure fluid is admitted by said valve from a suitable supply line 34 through a valve 35 to the outer ends of said cylinders to move their pistons and slides 5^a and 5^b inward, thereby engaging the torches A and B with the billet x. Solenoids 31 and 32 are connected by a common conduit 36, solenoid 31 being connected through contact d1 in a conduit 37 with conduit 17, and solenoid 32 through contact d2 in conduits 38, 39 with conduit 20.

As the torches A and B are moved into engagement with the billet, they are self-ignited and begin preheating the billet preliminary to scarfing, said ignition and the preheating gases being supplied by mechanism provided in the mounting of the torches, not shown, and the preheating of the billet continues until the cutting oxygen is turned on, as hereinafter described, thereby defining a fixed and uniform preheat time for each operation of the scarfing apparatus.

Contact d2 also energizes solenoids 40^a and 40^b actuating fluid valves 41^a and 41^b to adjust the vertical position of the torches A and B, respectively, upon the billet, said solenoids being in circuit with conduits 17 and 38. Valve 41^a controls the supply 42 of high pressure and supply 43 of low pressure fluid to cylinder 7^a, and as actuated by contact d2 and solenoid 40^a, said valve closes off the high pressure fluid and admits low pressure fluid from supply 43. Similarly, valve 41^b controls an exhaust line 44 from cylinder 7^b and a supply 45 of low pressure fluid thereto, the latter position of the valve being defined by contact d2 through solenoid 40^b.

Hence, by means of valves 33, 41^a and 42^a, the torch slides 5^a and 5^b are adjusted through the respective fluid cylinders to bring the torches A and B into contact with the billet x, the pressure thereof upon the latter being adjusted to just permit the torches to ride the billet without injury to the said torches. Each of the valves 41^a and 41^b and their respective low pressure supplies 43 and 45 is provided with a pressure control including a solenoid valve 46 in circuit with a pressure relief switch 47 whereby the pressure of the fluid to said valves 41^a and 41^b may be

limited, said control devices being in circuit with conduits 38 and 17.

Relay D also closes a normally open third contact d3, in circuit with conduit 20 and a conduit 48, to actuate solenoid 49 and its valve 50, admitting fluid under pressure from supply 51 to pinch roll cylinder 11, causing the pinch roll 10 to engage the billet x.

The actuation of the foregoing takes place during a predetermined time interval, following which the timer T initiates the remaining operations in the scarfing cycle. Contact t1 of the said timer next closes to energize relay E, closing a single normally open contact e which energizes solenoid 52 connected to valve 35, thereby subjecting the cylinders 6^a and 6^b to low pressure fluid from supply 53, insuring sufficient pressure reduction upon the torches A and B to permit the billet x to be moved, said solenoid being in circuit with conduit 38 and with conduit 18 through a conduit 54. Likewise, contact e energizes a solenoid 55 through conduits 17 and 56, 54, moving valve 57 to open water sprays 58 surrounding the billet x immediately rearwardly of the plane of the torches A and B, the said water sprays being fed from a pressure supply line 59 for removal of slag as the scarfing progresses.

Contact t2 of the timer T next closes, energizing relay F having two normally open contacts f1 and f2. Contact f1 closes and energizes solenoid 60 opening valve 61 to admit cutting oxygen to the torches A and B, said solenoid being in circuit with conduits 62, 36, 17 and 19. Contact f2 closes and energizes conduit 24 to complete the circuit to the controller 25 and roller table motor 9, whereupon the billet x is moved through the scarfing torches A and B.

After a predetermined timing interval, contact t3 of timer T closes to energize relay G. Normally closed contact g1 of said relay opens to break the circuit 17, 48 to the pinch roll valve solenoid 49, permitting self-retracting pinch roll 10 to raise from contact with the billet x, and normally closed contact g2 opens to break the circuit 17, 24 to the roll table motor 9, preventing another billet from entering the torches A and B while the latter are still closed.

Contact t4 of the timer T is in circuit with the motor 30 and source 30*, and is normally closed and remains closed until contacts t1, t2 and t3 have closed to start the relays and apparatus which the latter control, whereupon contact t4 opens. The scarfing continues until the operator opens the master control switch 12, whereupon clutch 30 opens to reset the timer action. The operator gauges the time to stop the scarfing by observing the travel of the billet through the torches.

Upon opening switch 12, relay C is deenergized and the other relays are deenergized substantially instantaneously therewith, shutting off the oxygen supply to the torches, permitting the carriage motor 4 and roll table motor 9 to be operated from their controllers, the torch slides 5^a and 5^b are retracted by the reverse operation of their respective fluid cylinders, and the water sprays 58 are turned off. The automatic resetting timer T resets and is in readiness for the next scarfing operation, the time interval for returning the entire apparatus and control to normal being dependent only upon the speed of the relays and control devices.

By properly timing the intervals between the successively actuated relays, it is possible to provide a highly accurate control based upon the time interval necessary to initiate the scarfing

operation without over or under treatment, and without waste of the scarfing gases. In addition, when the scarfing apparatus is positioned in a continuous mill, the same may be located in spaced relation to a subsequent roll stand in accordance with the length of billet being treated, and thereby create a fixed interval for the operation of timer contact t_3 so that the table roller 8 and pinch roll 10 may be stopped as soon as the billet reaches the roll stand.

It should be noted that the timing of relay F to act subsequent to relays D and E insures the relief of clamping pressure upon the torch slides 5^a and 5^b so that when relay F starts the cutting oxygen, the torches will freely ride the billet without injury.

A further and important advantage of the present control system, operated from a single master switch, is the ability to immediately return the apparatus to normal in the event of trouble being encountered while scarfing, or at the completion of the scarfing cycle, by the simple expedient of opening said master switch.

Various changes and modifications are contemplated within the scope of the following claims.

We claim:

1. In apparatus for continuously scarfing billets and the like, movable scarfing torches and electrically operable means controlling movement of the same in relation to the billet, electrically operable means for moving the billet in relation to the torches, electrically operable means controlling the supply of cutting oxygen to the torches, a source of electrical power, a control circuit including a timing device interconnecting and automatically actuating all of said electrically operable means in predetermined timed sequence while said circuit is energized, and a single pole switch in series with said power source and control circuit for instant interruption of said circuit, whereby the timing device is reset, the flow of oxygen is shut off, and the torches are retracted from the work.

2. In apparatus for continuously scarfing billets and the like, movable scarfing torches and electrically operable means controlling movement of the same in relation to the billet, electrically operable means for moving the billet in relation to the torches, electrically operable means controlling the supply of cutting oxygen to the torches, a source of electrical power, a control circuit including a plurality of relays and a timing device interconnecting and actuating all of said electrically operable means in predetermined timed sequence while said circuit is energized, means for automatically resetting the timing device upon interrupting said circuit, and a single pole switch in series with said power source and control circuit for instant interruption of said circuit, whereby the operation of all of said means may be arrested simultaneously.

3. Apparatus for scarfing billets or the like comprising a plurality of scarfing torches, means for moving the torches in relation to the billet, means for moving the billet in relation to the scarfing torches including adjustable pressure means for regulating the engagement of the

torches with the billet, means for supplying cutting oxygen to the torches, a control circuit, a single control switch for controlling the flow of current to said circuit, a timing relay in said circuit, means actuated by the closing of said switch for starting the timing relay in operation, a second means actuated by the closing of said switch for moving the torches into contact with the billet to preheat it, means operable by said timing relay after a predetermined time interval to supply cutting oxygen to the torches and move the billet in relation to the scarfing torches, means operable by said timing relay after a second predetermined time interval to stop the movement of the billet, and means operable by the opening of said switch at any time during the scarfing cycle for resetting the timing relay, shutting off the oxygen flow to the torches, and retracting the torches from the billet.

20 4. Apparatus for scarfing billets or the like comprising a plurality of scarfing torches, means for moving the torches in relation to the billet, means for moving the billet in relation to the scarfing torches including adjustable pressure means for regulating the engagement of the torches with the billet, means for supplying cutting oxygen to the torches, a control circuit, a single control switch for controlling the flow of current to said circuit, a timing relay in said circuit, means actuated by the closing of said switch for starting the timing relay in operation, a second means actuated by the closing of said switch for moving the torches into contact with the billet to preheat it, means operable by said timing relay after a predetermined time interval to spray water on said billet, means operable by said timing relay after a second predetermined time interval to supply cutting oxygen to the torches and move the billet in relation to the scarfing torches, means operable by said timing relay after a third predetermined time interval to stop the movement of the billet, and means operable by the opening of said switch at any time during the scarfing cycle for resetting the timing relay, shutting off the water spray, shutting off the oxygen flow to the torches, and retracting the torches.

Certificate of Correction

Patent No. 2,424,270.

July 22, 1947.

GEORGE C. EHEMANN, JR., ET AL.

It is hereby certified that error appears in the printed specification of the above numbered patent requiring correction as follows: Column 5, lines 61 and 62, claim 2, strike out the words "the operation of all of said means may be arrested simultaneously" and insert instead *the timing device is reset, the flow of oxygen is shut off, and the torches are retracted from the work*; and that the said Letters Patent should be read with this correction therein that the same may conform to the record of the case in the Patent Office.

Signed and sealed this 21st day of October, A. D. 1947.

[SEAL]

THOMAS F. MURPHY,
Assistant Commissioner of Patents.
